UNITED STATES PATENT OFFICE.

ELMER W. JOHNSON, OF TRACY, MINNESOTA.

CAMPER'S BACK REST.

Application filed August 30, 1926. Serial No. 132,502.

The present invention relates to a camper's back-rest and has for its principal object to provide a structure whereby a person may sit on the ground without soiling the clothes and may have a comfortable back-rest.

Another very important object of the invention lies in the provision of a structure of this nature which may be folded into a compact form so as to be conveniently carried about in an automobile or the like.

A still further very important object of the invention lies in the provision of a camper's back-rest which is exceedingly simple in its construction, strong and durable, efficient and reliable, easy to manipulate, inexpensive to manufacture, and otherwise well adapted to the purpose for which it is designed.

With the above and numerous other objects in view as will appear as the description proceeds, the invention resides in certain novelties of construction, and in the combination and arrangement of parts as will be hereinafter more fully described and claimed.

In the drawing:

Figure 1 is a perspective view of the camper's back-rest showing the same ready for use,

Figure 2 is a perspective of the device folded.

Referring to the drawing in detail it will be seen that the letter F denotes generally a rectangular frame including a pair of spaced parallel sides 5, a cross member 6 at one end of the sides and a cross member 7 adjacent the other end of the sides. A roller 8 is journaled in said other end of the sides 5 and has pins 9 or other suitable elements at its ends which prevent the displacement of the roller but allow it free rotation. A piece of canvas or similar material is indicated by the numeral 10 and has one end suitably fixed to the roller 8 so that it may be extended as shown in Figure 1 or rolled up about the roller as is shown in Fig. 2. A prop structure is indicated generally by the letter P and includes a pair of prop legs 11 pivot-ed at one end as at 12 to intermediate portions of the sides 5 adjacent the end across which the cross member 6 is disposed. The spring

ends of the prop legs 11 are provided with notches 14 and a cross rod 15 extends across their free ends for bracing the prop legs 55 with respect to each other. A cord, rope, or other flexible member 16 passes through openings 17 provided in the sides 5 adjacent the cross members 7 and the ends of the flexible members 16 are knotted as at 18. It 60 will be seen that when the prop structure P is extended to the position shown in Fig. 1 the flexible members may be engaged in the notches 14 so that a strong and durable, besides a comfortable, back-rest is formed and 65 the canvas seat 10 may be stretched out on the ground so that a person may sit thereon and rest against the back-rest thus formed.

It will be seen that the device when folded is rather compact and either end or both 70 ends of the cord may be pulled so as to be tied together if desired for holding the structure in its folded position. The present embodiment of the invention can now be clearly understood by those skilled in this art 75 without a more detailed description and this embodiment has been illustrated merely by way of example since in actual practice it attains the features of advantage enumerated as desirable in the statement of the invention and the above description. It will be apparent that numerous changes in the details of construction, and in the combination and arrangement of parts may be resorted to without departing from the spirit of the 85 invention as hereinafter claimed or sacrificing any of its advantages.

Having thus described my invention what I claim as new is:

A device of the class described, including, 90 in combination, a rectangular frame, a prop structure pivotally engaged with an intermediate portion of the frame, a flexible member having ends piercing openings in the sides and said ends knotted, said prop structure being provided with notches for receiving intermediate portions of the flexible member so that said flexible member will function as a brace between the frame and prop structure, a roller journaled in one 95 end of the frame and a flexible seat engaged with said roller.

In testimony whereof I affix my signature.

ELMER W. JOHNSON.
